(57) **CLAIM**

The ornamental design for a vehicle tire, as shown and described.

DESCRIPTION

1. Vehicle tire
1.1 is a perspective view of a vehicle tire embodying our new design;
1.2 is a partial and enlarged front elevation view thereof;
1.3 is a left side elevation view thereof;
1.4 is a right side elevation view thereof;
1.5 is a front elevation view thereof; and
1.6 is a top plan view thereof.
